UNITED STATES PATENT OFFICE.

JOHN M. BARBER, OF ST. CHARLES, ILLINOIS.

WIRE-FENCE MACHINE.

SPECIFICATION forming part of Letters Patent No. 681,081, dated August 20, 1901.

Application filed May 17, 1901. Serial No. 60,714. (No model.)

To all whom it may concern:

Be it known that I, JOHN M. BARBER, a citizen of the United States, residing at St. Charles, in the county of Kane and State of Illinois, have invented a new and Improved 5 Wire-Fence Machine, of which the following is a full, clear, and exact description.

My invention relates to machines for twisting wire strands in the manufacture of picket fences, and has for its object to provide a simple, light, and efficient machine of the above-indicated class in which the movable parts are so arranged as to minimize, if not altogether avoid, side strains and to reduce 15 friction.

The invention will be fully described hereinafter and the features of novelty pointed out in the appended claims.

Reference is to be had to the accompanying 20 drawings, forming a part of this specification, in which similar characters of reference indicate corresponding parts in both the views.

Figure 1 is a perspective view of my improved wire-fence machine in operation, and 25 Fig. 2 is a cross-sectional plan on the line 2 2 of Fig. 1.

The machine-frame comprises two uprights A A', one of which is shorter than the other, both of the uprights being angular in cross- 30 section—for instance, hexagonal, as shown. From the top of the longer upright A an arm C extends, first horizontally toward the other upright A' and then downward until it meets the upper end of the shorter upright A'. From 35 that point the member C extends horizontally from one upright to the other. The said member C is double and is formed at its ends, as well as at that portion which engages the upper end of the upright A', with clamping portions C' of a shape corresponding to the angular form of the uprights. The two sections of the member C are connected adjacent to the uprights by screws and bolts D or by any other suitable means. At that part of the 40 member C which is farthest away from the upright A a sprocket-wheel E is journaled in said member, and on the shaft of said sprocket-wheel is mounted an operating-crank F. At suitable intervals below the bottom part of 45 the member C the uprights A A' are connected by braces or cross-arms G, each of which is double and provided at its free end with a

clamping portion G' to engage the corresponding upright. At the center the cross-arms G, as well as the horizontal lower portion of the member C, are provided with bearings, as shown at G² in Fig. 2, the said bearings receiving hub portions H', projected from sprocket-wheels H, which are mounted to rotate between the bearings G², the latter being 55 appropriately spaced for this purpose. A similar construction is provided at the upper horizontal portion of the member C, and it will be understood that all the sprocket-wheels H are located substantially in vertical alignment. The sections of the cross-arms G are connected adjacent to the uprights A A' by bolts I and nuts I'. A chain J passes over all of the sprocket-wheels E and H, and one run of the chain is substantially vertical, while the 60 other run engages the two lowermost sprocket-wheels H on one side and then passes alternately from one side to the other as it engages the several other sprocket-wheels. In order to guide the vertical run of the chain J 65 and to keep it from contact with the sprocket-wheels H and with the other run of the chain at points where such contact is not desired, I provide the lower portion of the member C and the cross-arms G with inward projections 70 G³, which, as shown in Fig. 2, prevent a movement of the vertical run of the chain toward the other run thereof. Each of the sprocket-wheels H has its web provided within the hub H' with a plurality of apertures H², suitable for the reception of the wire to be 75 twisted.

In operation the frame is set up transversely of the fence, so that the centers of the sprocket-wheels H will be on lines connecting adjacent fence-posts, and then the wires K are passed through the apertures H² and fastened to the tension-post L in the usual manner. Thereupon the crank F is rotated, thus causing the wire to be twisted in 80 the ordinary manner. Inasmuch as all the sprocket-wheels H are located in vertical alignment there is very little side strain, if any, and the particular journaling of the sprocket-wheels enables them to turn with 85 very little friction, while interference of the vertical run of the chain J with the other moving parts is rendered impossible by the use of the projections G³.

Having thus described my invention, I claim as new and desire to secure by Letters Patent—

1. A wire-fence machine, comprising two uprights of unequal length, a connecting member extending from the top of one upright to the top of the other, and provided with an outward bend, a driving-wheel journaled in said member at the bend thereof, cross-arms connecting the two uprights at intervals, guide-wheels journaled in said cross-arms and in said connecting member, said guide-wheels being all located in vertical alinement and provided with apertures for the passage of wires, and a driving connection extending in contact with the driving-wheel and the guide-wheels.
2. The combination of the uprights, the cross-arms each made of two sections ar-

ranged to clamp the uprights between them and provided with centrally-located bearings and with projections at one side of the bearings, the latter being spaced from each other, twisting-wheels having hubs journaled in said bearings while the bodies of the wheels extend between mating bearings, a driving-wheel journaled in the frame, and a chain engaging the driving-wheel and the twisting-wheels, the two runs of said chain passing on opposite sides of the projections on the sections of the connecting-arms.

In witness whereof I have signed my name to this specification in the presence of two subscribing witnesses.

JOHN M. BARBER.
